United States Patent Office

Des. 208,853
Patented Oct. 10, 1967

208,853

MOTOR VEHICLE

Robert Von Heck, 11827 Runnymede St.,
North Hollywood, Calif. 90028

Filed Nov. 21, 1966, Ser. No. 4,755

Term of patent 14 years

(Cl. D14—3)

Ex. 1

Ex. 2

FIGURE 1 is a front perspective view of the motor vehicle showing the new design;

FIGURE 2 is a rear perspective view of the article showing the new design;

FIGURE 3 is a side elevational view of the article;

FIGURE 4 is a plan view of the design article;

FIGURE 5 is a front elevational view of the article; and

FIGURE 6 is a rear elevational view of the article.

The dominant features of my design reside in the portions shown in full lines.

I claim:

The ornamental design for a motor vehicle, as shown and described.
